DISPENSING CAP FOR A CONTAINER

Frank W. Derenski, 11009 Morrison St.,
North Hollywood, Calif. 91601

Filed Dec. 16, 1968, Ser. No. 14,967

Term of patent 14 years

Int. Cl. D9—02

U.S. Cl. D9—275

FIG. 1 is a perspective view of a dispensing cap for a container embodying my new design;

FIG. 2 is a side elevational view;

FIG. 3 is a front elevational view;

FIG. 4 is a rear elevational view;

FIG. 5 is a sectional view taken along the line 5—5 of FIG. 3; and

FIG. 6 is a top plan view thereof.

In the figures the cap is shown in pouring position.

I claim:

The ornamental design for a dispensing cap for a container, as shown and described.
